UNITED STATES PATENT OFFICE

DARWIN G. GRISWOLD, OF WALLINGFORD, CONNECTICUT, ASSIGNOR TO R. WALLACE & SONS MFG. CO., OF WALLINGFORD, CONNECTICUT, A CORPORATION OF CONNECTICUT

POLISHING MACHINE FOR SPOONS

Application filed July 12, 1929. Serial No. 377,669.

This invention relates to polishing machines and particularly to a polishing machine adapted to operate upon different portions of a spoon bowl, or the like, with successive polishing wheels.

In existing types of automatic polishing machines small objects to be polished are attached to a carrier belt which brings the work into contact with various polishing wheels which are located so as to polish various surfaces of the work. Such machines, while satisfactory for polishing plane and some convex surfaces, are not adapted to polish concave surfaces such as the interiors of spoon bowls, or convex surfaces such as the exteriors of spoon bowls.

A primary object of this invention is to provide a completely automatic machine adapted to polish the bowl of a spoon, or the like, by successive operations upon the convex and concave surfaces thereof by a plurality of consecutively used rotating polishing wheels. Other objects and features of the invention will be pointed out or will become apparent upon a reading of the specification.

Briefly stated, in a preferred form of the invention I employ a plurality of power-driven polishing wheels, means to reciprocate these polishing wheels, a power-driven carrier belt, means for advancing the same step by step past the polishing wheels, a plurality of work holders, each being pivoted about an axis and adapted to raise a piece of work from the carrier belt and hold the work in operative position in contact with a polishing wheel and return the work to the carrier belt, means to oscillate the work holders about a second axis, automatic means to turn the work upside down during its movement along the machine, and an abradant supplying means, the operation of the work holders about both axes and the operation of the belt and of the abradant supplying means being automatically timed and controlled.

In the accompanying drawings annexed hereto and forming a part of this specification, I have shown my invention embodied in an automatic machine for completely polishing the inner and outer surfaces of a spoon

bowl, but it will be understood that the invention can be otherwise embodied and that the drawings are not to be construed as defining or limiting the scope of the invention, the claims appended to this specification being relied upon for that purpose.

Referring to the figures of the drawings:

Fig. 1 is a plan view of a portion of the machine, the abradant supplying mechanism being omitted;

Fig. 1^a is a continuation of Fig. 1, showing a similar view of the remainder of the machine;

Fig. 2 is a transverse sectional view of the machine showing a polishing wheel and means for advancing a spoon being polished into position against a wheel;

Fig. 3 is a front elevation of a portion of the carrier belt for the work and its operating means;

Fig. 4 is a perspective view of the work supporting and conveying belt shown in Fig. 3;

Fig. 5 is a sectional view showing a portion of the oscillating means for the work holding and transfer means;

Fig. 6 is a side elevational view of the work clamping and transferring means showing a spoon in contact with a wheel and having a portion of the inner surface of the bowl polished;

Fig. 7 is a series of fragmentary sectional views showing a wheel engaging a portion of the inner surface of a spoon bowl, the work and its supporting means being shown in successive oscillated positions;

Fig. 8 shows a spoon, the portion of the bowl operated upon by the wheel shown in Fig. 7 being unshaded;

Fig. 9 includes a series of fragmentary sectional views similar to Fig. 7 showing another wheel operating upon a different portion of the inside or concave surface of the spoon bowl;

Fig. 10 shows a spoon, the portion operated upon by the wheel in Fig. 9 and by the previous wheel being unshaded;

Fig. 11 is a series of views similar to Fig. 7 showing the operation of a third polishing

wheel upon a different section of the inside surface of the spoon bowl;

Fig. 12 shows a spoon, the surface operated on by the wheel in Fig. 11 and by the previous wheels being unshaded;

Fig. 13 is a fragmentary view of the work holding and transferring mechanism with the spoon shown turned over and held in position for operation upon its outer or convex surface;

Fig. 14 is a series of fragmentary views showing a wheel operating upon one portion of the outside surface of a spoon bowl;

Fig. 15 shows a spoon, the portion polished by the wheel shown in Fig. 14 being unshaded;

Fig. 16 is a series of views similar to Fig. 14 showing the wheel operating upon another portion of the outside surface of the spoon bowl;

Fig. 17 shows a spoon, the part operated upon by the wheel shown in Fig. 16 and by the preceding wheel being unshaded; and

Fig. 18 is an isometric view showing the spoon turning device associated with the traversing carrier belt for the spoons.

In the above mentioned drawings, I have shown but one embodiment of the invention which is now deemed preferable, but it is to be understood that changes and modifications may be made within the scope of the appended claims without departing from the spirit of the invention.

In said illustrative drawings, 10 indicates a frame on which the polishing mechanism is supported. Polishing wheels 20 are mounted on spindles 23 which are journaled in heads 21 and 24. These heads are attached to members 22 which are supported in sleeves 45 attached to the frame. In the preferred embodiment illustrated in the drawings, there are five of these wheels 20, of any standard type. As shown in Fig. 1^a two of the wheels 20 are mounted to rotate upon axes 40 obliquely disposed relative to the axis of the members 22. The heads 24 for these wheels are preferably pivotally mounted on vertical axes and may be clamped in any desired angular position. The driving means for the polishing wheels 20 may comprise a series of pulleys (not shown) directly above the machine connected by suitable individual belts to small pulleys 25 mounted on the spindles 23.

11 is a carrier belt which moves in the direction indicated by the arrow in Figs. 1, 1^a, and 3. It consists of a plurality of metal links pivotally connected together, each link being adapted to receive a work piece to be polished. Each link is provided with plates 12 upstanding at opposite sides of the link, and slotted as shown in Figs. 4 and 18, the size of the slots in the links being chosen to accommodate different portions of the work pieces being operated on. The carrier belt

is supported on horizontal surfaces of the frame and passes around sprocket wheels carried on the shafts 97 and 14. One of these sprocket wheels is shown at 13 in Fig. 3. This sprocket wheel is driven by a ratchet-wheel 15 on the shaft 97. Pivoted on the shaft 97 is a lever 17 to which is pivoted a driving pawl 16. A spring 18 holds the pawl 16 toward the ratchet-wheel 15. The lever 17 also carries a roller 67 which engages with a cam groove in a cam drum 66 on a cam shaft 60. The cam shaft 60 is driven from a main drive shaft 52 by means of gears 57 and 59 and idler gear 58 (see Fig. 2). A pulley 56 on the shaft 52 is driven by a belt from any convenient source of power. By means of this mechanism the carrier belt is advanced step by step, the length of each step being equal to the length of one link of the belt.

In order to transfer the work pieces being operated on from their positions upon the carrier belt to their operative or polishing positions and hold them in contact with the polishing wheels and return them to their places in the carrier belt, work holders 26 are provided. Fixedly attached to the rear end of each work holder is a shaft 35 which is pivotally mounted within a sleeve 27. The sleeves 27 are pivotally mounted upon horizontal axes determined by pointed screws 28. The screws 28 are secured in brackets 28^a fixed to the tie rod 94. The work holders 26 are adapted to be oscillated about the axes of the screws 28 and their oscillation is controlled by connecting rods 29 attached at their upper ends to the sleeves 27. These rods have their lower ends attached to the forward ends of arms 30 which are rigidly attached to a shaft 65. The shaft 65 is oscillated by an arm 64 having a roller 100 which contacts with cam plates 63 secured on the cam shaft 60. The roller 100 is held against the cam plates 63, and the work pieces are elevated and held against the wheels 20, by weights 31 on the rearward extensions of the sleeves 27. These weights are movable toward and from the axes of oscillation of the sleeves 27 so that the pressure of the work against a wheel may be controlled within wide limits.

The work is held in the work holders by means which I shall now describe. 41—41 are rods extending between the work holders 26—26 and supported over the belt 11 by brackets 89 attached to the frame. The ends of the rods 41—41 adjacent the work holders 26—26 terminate in troughs 96—96 (see Figs. 1 and 6). Work clamping members 32 are pivoted at 90 to the outer ends of the work holders 26 and are provided with springs 95 which push their free ends downward. These clamping members have horizontally extending lugs 32^a which engage in the troughs 96 and prevent the clamping mem-

bers from engaging with the work pieces while the work pieces are in position in the belt 11. Movement upward of the work holders 26 permits resilient engagement of the free ends of the members 32 with the work pieces so that the work may be retained firmly in position in the work holders. As shown in Figs. 6 and 13, the holders 26 have moulded surfaces 33 conforming to portions of the 10 surface of a work piece so that the work pieces are maintained rigidly in position by the spring-pressed members 32.

The work holders 26 extend on opposite sides of the carrier belt 11 and are provided 15 with wide and deep depressions between their upward extending portions 34 so that they can have considerable oscillatory movement in a vertical plane without obstruction by the carrier belt 11.

20 In order to increase the surface polished by a wheel, means are provided to automatically move either the work holders 26 or the polishing wheels 20 so that the wheels will move both longitudinally and laterally relatively to 25 the work. In the particular form shown in the drawings, the wheels are moved longitudinally relatively to the work by reciprocating the wheels, and the wheels are moved laterally relatively to the work by oscillating the 30 work holders.

The means for reciprocating the wheels are shown in Fig. 2. Fastened to the shaft 52 is a crank 51 which drives the connecting rod 53 which oscillates the arm 54 and the shaft 47 which is attached thereto. Fixed to the shaft 47 are arms 48 which drive connecting rods 50 which are pivoted at 49 to the members 22, the pivots 49 extending through openings 46 in the sleeves 45. By means of this mechanism the polishing wheels are reciprocated so as to traverse over portions of the work. Rod 53 is adapted to be connected to the arms 51 and 54 at different points and by proper adjustment of the points of connection the oscillation of the shaft 47 may be varied through wide limits. Similarly the connecting rods 50 are adapted to be connected to the arms 48 at a number of different points so that individual adjustment of the stroke of 50 the wheels 20 is provided.

The means for oscillating the work holders 26 to increase the lateral polishing effect of the wheels 20 are shown in Figs. 2 and 5. Arms 37 have yokes 36 at their upper ends which are pivoted to the shafts 35, the axes of the pivots coinciding with the axes established by the screws 28. The lower ends of the arms 37 pass through holes in studs 99 which are pivoted at 38 to a bar 39. This bar 39 extends throughout the length of the machine and is reciprocated by a roller 62 coacting with a cam drum 61 on the cam shaft 60, with the result that the work holders 26 are oscillated about the axes of the shafts 35. The work holders are therefore automatically

oscillated about two mutually perpendicular axes, viz; the axes of the shafts 35 and the axes of the screws 28.

After the work pieces have been operated upon by the polishing wheels, the work holders 26 are oscillated downward by the cam 63 to return the work to the carrier belt 11. The lugs 32^a on the work clamping members 32 drop into the troughs 96, and further downward movement of the work holders drops the work out of contact with the members 32 and into the slots of the plates 12 on the carrier belt 11. Movements of the carrier belt are timed to occur between movements of the work holders 26 so that as soon as the latter have returned the work pieces to their positions on the belt 11 the belt is actuated thus advancing all of the work pieces to their next positions. Usually a plurality of individual wheels must be used to completely polish the 80 inside surface of a spoon bowl, two obliquely mounted wheels engaging the heel of the bowl and a third wheel engaging the tip portion.

After a spoon has been operated on by the wheels to completely polish the inside surface 90 of the bowl, it is necessary to turn the spoon upside down in order that the convex surface of the bowl may be polished. For this purpose I interpose a spoon turning device in the path of the carrier belt 11. As a spoon moves forward on the belt 11 the edge of the bowl will come in contact with a fixed abutment 40. (See Fig. 18.) As the point of contact is below the points of support of the spoon in the plates 12 the movement of the belt 100 will cause the spoon to turn over to the second position shown in Fig. 18. The handle of the spoon is prevented from movement upward out of the slots 12 during this turning operation by the rod 41, and a plate 42 engages the tip end of the bowl to keep the bowls substantially in alignment. When turned over the spoon is in position for polishing by the remaining wheels 20. The surfaces 33 of the work holders which hold the 110 spoons while the convex surfaces of the bowls are being polished are varied to fit the spoons in their reversed position.

As the polishing operations upon different portions of a spoon are similar except that a wheel may be positioned differently to engage a different portion of the spoon bowl, no further description of the operation at each station will be given. The carrier belt, the wheels, and the work holders are all timed to move in accordance with a predetermined cycle so that the work holders simultaneously pick up spoons from the carrier belt and move them into proper positions relative to the wheels 20 for individual polishing operations. During the polishing operation the work holders are simultaneously oscillated laterally, the amount of lateral oscillation for each work holder being controlled by the position of the corresponding stud 99. After the com- 120 125 130 135 140 145 150

pletion of the individual polishing operations which are timed to permit effective and complete polishing of the portions of the spoons engaged by the individual wheels 20, the transfer members 26 are again simultaneously moved, this time being returned to their lower positions, whereupon the spoons held therein are released and permitted to lie within the slots 12 in the links of the carrier belt 11. The carrier belt 11 is then actuated to advance by one link thereby bringing a different spoon beneath each polishing wheel, whereupon the transfer members 26 are again elevated. After being presented to each of the polishing wheels, the spoons are discharged into the chute 101 which is positioned adjacent to the sprocket wheel 13. The cam drums 61 and 66 and the cam plates 63 are all attached to the shaft 60 and their cam surfaces are positioned so as to automatically secure the sequence of movement of the work holders 26 and of the carrier belt 11 which has just been described.

The machine is also provided with automatic means for periodically supplying abradant material to the polishing wheels. These means are indicated generally at 71 in Fig. 2.

I have thus produced a completely automatic polishing machine which will perform a multiplicity of various polishing operations without attention except to place the work in the carrier belt, which can be done by unskilled labor.

I claim:

1. A polishing machine for spoons comprising in combination, a plurality of polishing wheels, a conveying belt for said spoons, automatic spoon holding and transferring means adapted to remove a spoon from said belt and hold said spoon in contact with a wheel and replace said spoon upon said belt, means to oscillate said holding and transferring means while in position holding a spoon against a wheel to polish the spoon from side to side, and means to move said wheels in a direction longitudinally of the spoons in said holding and transferring means while contacted by said spoons.

2. A polishing machine for spoons comprising in combination, a plurality of polishing wheels, conveying means to position said spoons for successive operations by said wheels, means on said conveying means loosely engaging the handles of said spoons, a fixed abutment in the path of the bowls of said spoons, and means limiting endwise and vertical movement of said spoons while engaged by said abutment, whereby advancing movement of said conveying means will turn said spoons upside down.

3. A polishing machine comprising a power-driven polishing wheel, automatic means to reciprocate said wheel, a work-carrier belt, automatic means to intermittently advance said belt, a work holder, and auto-

matic means to oscillate said holder about each of two different axes.

4. A polishing machine comprising, in combination, a polishing wheel, a work-carrier belt, and automatic means adapted to remove a work piece from said belt and hold said work piece in contact with said polishing wheel and replace said work piece upon said belt. 70

5. A polishing machine comprising, in combination, a polishing wheel, a work-carrier belt, automatic means adapted to remove a work piece from said belt and hold said work piece in contact with said polishing wheel and replace said work piece upon said belt, and automatic means to intermittently advance said belt. 75 80

6. A polishing machine comprising, in combination, a polishing wheel, a work-carrier belt, an automatic work holder adapted to remove a work piece from said belt and hold said work piece in contact with said polishing wheel and replace said work piece upon said belt, and means to automatically oscillate said work holder and work piece 85 while said work piece is engaged by said wheel. 90

7. A polishing machine comprising, in combination, a polishing wheel, a work-carrier belt, automatic means adapted to remove a work piece from said belt and hold said work piece in contact with said polishing wheel and replace said work piece upon said belt, and automatic means to reciprocate said 95 100 polishing wheel.

8. A polishing machine comprising, in combination, a polishing wheel, a work-carrier belt, automatic means adapted to remove a work piece from said belt and hold said work piece in contact with said polishing 105 wheel and replace said work piece upon said belt, and automatic abradant supplying means.

9. A polishing machine comprising a plurality of power-driven polishing wheels, 110 means to reciprocate said polishing wheels, a power-driven carrier belt, means for advancing said belt step by step past said polishing wheels, a plurality of work holders each pivoted on an axis and adapted to raise the work 115 from said carrier belt to operative position in contact with a polishing wheel and to return the work to said carrier belt, and means to oscillate each of said work holders about a second axis, the operation of said work holders about each of said axis and of said carrier belt being automatically timed and controlled. 120

10. A polishing machine comprising a plurality of power-driven polishing wheels, 125 means to reciprocate said polishing wheels, a power-driven carrier belt, means for advancing said belt step by step past said polishing wheels, a plurality of work holders each pivoted on an axis and adapted to raise the work 130

from said carrier belt to operative position in contact with a polishing wheel and to return the work to said carrier belt, said work holders being operated by power in one direction and by gravity in the opposite direction, and means to oscillate each of said work holders about a second axis, the operation of said work holders about each of said axes and of said carrier belt being automatically timed and controlled.

11. A polishing machine comprising a plurality of power-driven polishing wheels, means to reciprocate said polishing wheels, a power-driven carrier belt, means for advancing said belt step by step past said polishing wheels, a plurality of work holders each pivoted on an axis and adapted to raise the work from said carrier belt to operative position in contact with a polishing wheel and to return the work to said carrier belt, said work holders being operated by power in one direction and by gravity in the opposite direction, means to oscillate each of said work holders about a second axis, and abradant supplying means, the operation of said work holders about each of said axes and of said carrier belt and of said abradant supplying means being automatically timed and controlled.
